(57) **CLAIM**

The ornamental design for a light emitting diode lamp, as shown and described.

DESCRIPTION

FIG. 1 is a perspective view of a light emitting diode lamp showing the new design.

FIG. 2 is a front view thereof.

FIG. 3 is a rear view thereof.

FIG. 4 is a right side view thereof, and the left side view being a mirror image of the right side view.

FIG. 5 is a top plan view thereof, and bottom plan view being a mirror image of the top plan view.

FIG. 6 is an enlarged cross-sectional view taken along line 6—6 in FIG. 2 with the internal parts omitted.

FIG. 7 is an enlarged cross-sectional view taken along line 7—7 in FIG. 2 with the internal parts omitted, wherein the portion having the double slanted lines are transparent.

FIG. 8 is an enlarged front view of the portion enclosed by lines 8—8 in FIG. 2, wherein the portion having the double slanted lines are transparent; and,

FIG. 9 is an end elevational view taken along line 9—9 in FIG. 8, wherein the portion having the double slanted lines are transparent.
